[57] CLAIM

The ornamental design for a carton having additional rectilinear corners, as shown and described.

DESCRIPTION

FIG. 1 is a top, side and end perspective view of the carton having additional rectilinear corners;

FIG. 2 shows an opposite end view of the carton having additional rectilinear corners;

FIG. 3 shows an opposite side view of the carton having additional rectilinear corners;

FIG. 4 shows a top plan view of the carton having additional rectilinear corners; and,

FIG. 5 shows a bottom plan view of the carton having additional rectilinear corners.

The broken line showing on FIG. 1 is for illustrative purposes only and forms no part of the claimed design.
